CLAIM

The ornamental design for a gaming controller as shown and described.

DESCRIPTION

FIG. 1 is a top perspective view of the gaming controller of the new design;

FIG. 2 is a top plan view thereof;

FIG. 3 is a bottom plan view thereof;

FIG. 4 is a front elevation view thereof;

FIG. 5 is a rear elevation view thereof;

FIG. 6 is a left elevation view thereof; and,

FIG. 7 is a right elevation view thereof.

The broken lines in the drawings depict portions of the gaming controller that form no part of the claimed design.
